US00D360036S

United States Patent [19]

Doria

[11] Patent Number: Des. 360,036

[45] Date of Patent:  Jul. 4, 1995

[54] COMBINED MASSAGER AND CASE FOR SKIN TREATMENT

3,763,854 10/1973 Welch 601/6
4,003,373 1/1977 Spelio ..... 601/6 X

[75] Inventor: Alessandro Doria, Milano, Italy

Primary Examiner—Stella Reid
Attorney, Agent, or Firm—Juettner Pyle Lloyd & Piontek

[73] Assignee: Daniels S.P.A., Milan, Italy

[57] CLAIM

[] Term: 14 Years

The ornamental design for combined massager and case for skin treatment, as shown.

[21] Appl. No.: 17,129

DESCRIPTION

[22] Filed: Jan. 6, 1994

FIGS. 1 and 2 are perspective views of the overall design of the present invention;

[30] Foreign Application Priority Data

Jul. 22, 1993 [XH] Hague Agreement DM/026767

[52] U.S. Cl. D24/200

[58] Field of Search D24/200, 211, 212, 213,
D24/214, 215; 601/6, 7, 9, 14; 604/313, 315,
316

FIGS. 3 and 4 are perspective views of the case portion of the present invention;

FIGS. 5-10 are top, front, bottom, rear end, left side, and right side views of the case portion of the present invention;

FIGS. 11-17 are, respectively, perspective, top, bottom, side, side, end and end views of a portion of the massage apparatus of the present invention; and,
